UNITED STATES PATENT OFFICE

CLARENCE W. MENSING, OF FORT WAYNE, INDIANA, ASSIGNOR TO S. F. BOWSER & COMPANY, INC., OF FORT WAYNE, INDIANA, A CORPORATION OF INDIANA

DESIGN FOR A CASING FOR A LUBRICANT DISPENSER

Application filed July 24, 1929. Serial No. 32,191. Term of patent 14 years.

To all whom it may concern:

Be it known that I, CLARENCE W. MENSING, a citizen of the United States, residing at Fort Wayne, in the county of Allen and State of Indiana, have invented a new, original, and ornamental Design for a Casing for a Lubricant Dispenser, of which the following is a specification, reference being made to the accompanying drawing, forming a part thereof.

In the accompanying drawing, Fig. 1 is a side elevation of a casing for a lubricant dispenser, showing my new design; Fig. 2 is an end elevation thereof.

I claim:

The ornamental design for a casing for a lubricant dispenser, as shown.

Fort Wayne, Indiana, July 19, 1929.

CLARENCE W. MENSING.
